UNITED STATES PATENT OFFICE.

ALFRED LIEBMAN, OF NEW YORK, N. Y., ASSIGNOR TO AUTO KONTROL LOCK CORPORATION, A CORPORATION OF NEW YORK.

INDICATING LOCK.

Application filed July 29, 1921. Serial No. 488,257.

To all whom it may concern:

Be it known that I, ALFRED LIEBMAN, a citizen of the United States, residing at New York, in the county of New York and State of New York, have invented certain new and useful Improvements in Indicating Locks, of which the following is a full, clear, and exact description.

It is very desirable, in some instances, 10 that a person be able to tell at a glance whether or not a lock is in locked or unlocked condition, and particularly so with respect to vehicle locks wherein the operator wishes without trial to know the condition of the 15 lock in order to avoid the annoyance or danger of starting the vehicle while it is still locked.

An object of the invention is to provide a lock which will indicate its condition with 20 respect to the parts controlled thereby, and which is exceedingly simple, reliable, effective, durable and inexpensive, and to provide means by which existing locks can be readily and inexpensively converted into 25 indicating locks, and which is particularly adaptable to locks of the so called pin and cylinder type.

Other objects and advantages will be apparent from the following description and 30 the novel features of the invention will be particularly pointed out in claims.

In the drawing,

Fig. 1 is a side elevation, partly in section, of a cylinder lock constructed in accordance 35 with my invention.

Fig. 2 is an end elevation of the same.

Fig. 3 is a section taken substantially along the line *a—a* of Fig. 2.

Fig. 4 is an elevation of the indicator and 40 Fig. 5 is an elevation of a detail.

In the illustrated embodiment of the invention, a casing or support 1 is adapted to be secured in one of the parts to be locked and contains a rotatable element or barrel 2 45 that extends endwise therethrough, and preferably projects about $\frac{1}{16}$ inch from the forward face 3 of the casing. The cylinder or barrel 2 contains a key hole 4 into which a suitable key (not shown) may be inserted to 50 rotate the barrel, the latter rotatably mounting a cam 5 upon its end projecting rearwardly from the casing and carrying a disc 6 which engages with a pair of pins 7 (only one being shown) upon the cam and operates the cam between its operative posi-

tions. The cam has an arcuate groove or cut away portion 8 of approximately 180° extent, into which projects a pin 9 that is carried upon the rear wall of the casing and which limits the movement of the cam to a 60 half revolution. The disc 6 by playing between the pins 7 provides, in effect, a lost motion connection whereby a full rotation of the barrel will cause a half rotation of the cam. The cam 5, in its movements about 65 the barrel is adapted to operate other parts which lock or unlock the parts to be controlled by the device, the details of the control being immaterial to the present invention and therefore omitted in the interest of 70 brevity.

An indicator 10, preferably in the form of a disc, is provided with an eccentric aperture 11 which receives the forwardly projecting end of the barrel 2 so as to be rotatably 75 mounted thereon. A second disc 12 is secured by screws 13 to the forward end of the barrel so as to slightly overhang the indicator disc 10, and prevent its displacement from the end of the barrel. The disc 12 is 80 provided with countersunk holes 14 for the passage of the screws 13 and with an elongated aperture 15 to permit of the insertion of the key (not shown) into the keyhole. The disc 10 is provided with an arcuate slot 85 16 concentric with aperture 11 and extending approximately 180° about the aperture. A pin 17 which is carried by the forward face 3 of the casing projects into the slot 16 to limit the rotation of the disc 10 to approximately a half revolution. A pin 18 90 which is carried by the disc 12 projects rearwardly therefrom into the slot 16 to operate the disc 10 between the two limits of movement permitted by the pin 17. The 95 pins 17 and 18 are disposed adjacent opposite curved walls of the slot 16 and the sum of their diameters is less than the width of the slot so as to be able to pass one another in the slot with a small clearance. 100 The periphery of the disc 10 is preferably beveled as at 19 to provide a surface upon which suitable symbols or lettering 20 may be placed to indicate the meaning of the position of the disc.

In use, the casing 1 is inserted into and 105 suitably secured to one of the elements to be locked, or to a support, with the cam 5 in position to control the desired parts. When the cam 5 is in the position illustrated in 110

Fig. 1, the disc 10 will be in its upper or full position (Figs. 1 and 2) so as to display the symbols or letters 20 that represent that the parts controlled by the cam 5 are in locked condition, for example. The lock illustrated is particularly adapted for use in locking devices that are mounted upon the steering posts of vehicles, and because of the inclination of such posts the aperture 15 and slot 4 may make a small angle, such as about 20 degrees, with a line joining the center of the disc 10 when in its two extreme positions in order to have the disc 10 overhang the casing wall 3 lengthwise of the post in its two indicating positions. When it is desired to unlock the controlled parts, a key is inserted through aperture 15 into the slot 4 and rotated a full revolution which causes a full revolution of the barrel 2. The barrel 20 in so moving carries the cam 5 to a position 180° distant to unlock the controlled parts. The barrel also carries with it the attached disc 12, and the pin 18 upon this disc moves idly in the slot 16 until it reaches the opposite end thereof, which will be after a half revolution has been made, whereupon the engagement of the pin 18 with the end of the slot will cause the disc 10 to be rotated with the barrel through the remaining half revolution, and into the position shown in dotted lines in Figs. 1 and 2 which represents the unlocked indicating position. In this position the pin 17 will engage the end 16^a of the slot 16 and limit further movement in the same direction and the pin 18 by its engagement with the opposite end 16^b of the slot will prevent a return movement. The barrel is preferably locked in the indicated position whenever the key is removed 40 by tumblers or pins, (not shown), in a manner well known in the art and illustrated by way of example in U. S. Patent 608,069 to which reference may be had for further details. The disc 10 will therefore be positively held in its lower indicating position.

If it is desired to lock the controlled parts, the key is inserted into the slot 4 as before and given a complete reverse rotation. The disc 12 will be carried with the barrel and after moving through a half revolution the pin 18 will again engage the end 16^a of the slot 16 and during the remaining half revolution will carry the disc 10 with it to the full line position shown in Figs. 1 and 2. In this position the pin 18 will prevent a return movement of the disc 10, and the pin 17 by its engagement with the end 16^b of the slot 16 will limit further forward movement of the indicator disc, so that the disc will be positively held in this position also.

It will be obvious that various changes in the details and arrangements of parts of the embodiment herein described and illustrated, may be made by those skilled in the art with 65 in the principle and scope of the invention.

I claim:

1. In an indicating lock comprising a key operated barrel, an indicator mounted adjacent the barrel for movement between two positions in each of which it indicates a condition of the lock, and a connection between the indicator and the barrel whereby as the barrel is rotated to lock or unlock the parts controlled thereby the indicator will be shifted to indicate the condition of the lock.

2. An indicating lock comprising a key operated barrel, an indicator mounted adjacent the barrel for movement between two positions in each of which it indicates a condition of the lock, and a lost motion connection between the barrel and the indicator whereby as the barrel approaches the limit of its rotation to lock or unlock the parts controlled thereby the indicator will be shifted to and held in a position indicating the condition of the lock.

3. An indicating lock comprising a cylinder lock having a rotatable barrel, an indicator, means carried by the barrel for securing the indicator thereto for oscillation thereabout between two positions in each of which it indicates a condition of the lock, and a connection between the indicator and means whereby as the barrel is rotated to lock or unlock the parts controlled thereby the indicator will be shifted to indicate the condition of the lock.

4. An indicating lock comprising a cylinder lock having a rotatable barrel, an indicator, means carried by the barrel for securing the indicator thereto for oscillation thereabout between two positions in each of which it indicates a condition of the lock, said means and indicator having a lost motion connection whereby as the barrel approaches the limit of its rotation to lock or unlock the parts controlled thereby the indicator will be shifted to and held in a position indicating the condition of the lock.

5. An indicating lock comprising a cylinder lock having a rotatable barrel, an indicator, means carried by the barrel for securing the indicator thereto for oscillation thereabout, means for limiting the movement of the indicator between two positions in each of which it indicates a condition of the lock, said securing means and indicator having a lost motion connection whereby as the barrel approaches the limit of its rotation to lock or unlock the parts controlled thereby the indicator will be shifted to and held in a position indicating the condition of the lock.

6. An indicating lock comprising a lock having a rotatable barrel, an indicator disc, a second disc carried by the barrel for securing the indicator disc thereto for oscillation thereabout, means for limiting the movement of the indicator disc between two positions

in each of which it indicates a condition of the lock, said discs having a pin and slot connection whereby as the barrel approaches the limit of its rotation to lock or unlock the 5 parts controlled thereby the indicator disc will be shifted to and held in a position indicating the condition of the lock.

7. An indicating lock comprising a lock having a casing and a barrel rotatable therein, an indicator disc, a second disc carried by the barrel for securing the indicator disc thereto for oscillation thereabout, said indicator disc having therein a slot concentric with the axis of rotation of the disc 15 and extending approximately through 180° about said axis, a pin carried by said casing and extending into said slot for limiting oscillation of the disc to approximately 180° , and a pin carried by the second disc 20 and also extending into said slot to form therewith a pin and slot connection whereby as the barrel approaches the limit of its rotation to lock or unlock the parts controlled thereby the indicator disc will be shifted to 25 and held in a position indicating the condition of the lock.

8. An indicating lock comprising a lock having a casing and a barrel rotatable therein, an indicator disc, a second disc carried by the barrel for securing the indicator disc thereto for oscillation thereabout, said indicator disc having therein a slot concentric with the axis of rotation of the disc and extending approximately through 180° about 30 said axis, a pin carried by said casing and extending into said slot for limiting oscillation of the disc to approximately 180° , and a pin carried by the second disc and also extending into said slot to form therewith a 35 pin and slot connection whereby as the barrel approaches the limit of its rotation to lock or unlock the parts controlled thereby the indicator disc will be shifted to and held 40

in a position indicating the condition of the lock, said pins having diameters which are 45 sufficiently small to permit them to pass in said slot and being disposed to permit them to pass.

9. An indicating lock comprising a support and a member adapted to be rotated 50 therein between two positions, an indicator mounted adjacent the member for movement between two indicating positions, and a positive lost motion connection between the member and indicator for causing a movement 55 of the indicator to indicate the condition of the lock with respect to the parts controlled thereby whenever the member is shifted.

10. An indicating lock comprising two relatively moving members adapted by their 60 relative movement to lock or unlock parts controlled thereby, an indicator mounted for movement between two indicating positions, a pin and slot connection between the indicator and the movable one of said members 65 for causing a movement of the indicator from one to the other of its indicating positions whenever a change in the condition of the lock occurs and means for limiting the movement of the indicator in each direction. 70

11. An indicating lock comprising two relatively moving members adapted by their relative movement to lock or unlock parts controlled thereby, an indicator mounted for movement between two indicating positions, means for limiting movement of the indicator to said two positions and a lost motion connection between the indicator and the movable one of said members for causing a movement of the indicator to change its 80 indication when the condition of the lock is changed.

In witness whereof, I hereunto subscribe my signature.

ALFRED LIEBMANN.
